UNITED STATES PATENT OFFICE

2,577,712

APPARATUS FOR CONTROLLING FREENESS
OF PAPERMAKING STOCKClifton N. Nilson, Springfield, Mass., assignor to
Cheney Bigelow Wire Works, Springfield, Mass.,
a corporation of Massachusetts

Application May 17, 1947, Serial No. 748,775

3 Claims. (Cl. 92—46)

1

This invention relates to paper making and is directed more particularly to improvements in apparatus for determining and controlling the freeness of stock in paper making operations.

The principal object of the invention is the provision of means and apparatus for determining and adjusting or controlling the freeness of paper making stock before it is delivered to the paper making machine so that stock of the desired freeness will be delivered to the paper machine.

When in the manufacture of paper at the paper machine it is evident that the degree of freeness of the stock is not as desired, the procedure is to adjust the Jordan or other fiber treating apparatus in an attempt to provide stock of the desired freeness.

Not only may the freeness of stock effect the speed of production but the formation of the paper is dependent on freeness to a considerable extent and for numerous other reasons freeness is an important consideration. In any event, it is desired in paper making to provide a certain condition of freeness of stock and in an attempt to attain the desired condition the stock refining or treating apparatus used in preparing fibers is and must be adjusted.

As an example, an apparatus such as a Jordan engine is used for refining or preparing fibers and this consists essentially of a rotatable tapering plug having cutter bars cooperating with cutter bars of a shell in which the plug rotates. The plug is moved in and out longitudinally of the shell or adjusted in order to obtain different results.

In many cases the stock from the refining apparatus flows to a stock chest and then to the paper making machine. The results of the particular condition of freeness of the stock is usually determined at the wet end of the paper machine. While the refining machine may be adjusted in an attempt to provide the desired degree of freeness, there is the time lag between the refining apparatus and the paper machine so that the results of adjustment are not known presently and is objectionable.

That is, the refining step is remote from the paper making step and while adjustments may be made to prepare or refine the stock so as to provide the desired freeness, a very considerable amount of stock lies between the refining or conditioning step and the web forming step whereby the effects of a present adjustment to affect freeness cannot be known for a considerable time and when known it is entirely possible that the ad-

2

justment has not produced the desired freeness.

According to this invention, apparatus and a method is provided whereby as the stock refining or treating operation proceeds, the degree of freeness of the stock is determined and as the freeness varies from that desired the stock treating or refining apparatus such as a Jordan or the like is adjusted. In this way stock of the desired freeness will be produced and delivered to the paper making machine. To accomplish this, the apparatus of the invention is preferably located adjacent the refining or conditioning apparatus and stock delivered to the paper machine or machines is delivered simultaneously to the apparatus hereof. Thereby the stock is continuously tested or the freeness is continuously determined and adjustments are made as and when necessary in order that stock of desired and uniform freeness is delivered to the paper making machine.

With the foregoing and various other novel features and advantages and other objects of my invention as will become more apparent as the description proceeds, the invention consists in certain novel features of construction and in the combination and arrangement of parts as will be hereinafter more particularly pointed out in the claims hereunto annexed and more fully described and referred to in connection with the accompanying drawings wherein:

Fig. 1 is a plan view of apparatus embodying the novel features of the invention and adapted for the novel method;

Fig. 2 is a combined side elevational and longitudinal sectional view through the apparatus shown in Fig. 1;

Fig. 3 is a sectional elevational view on the line 3—3 of Fig. 1;

Fig. 4 is a sectional elevational view on the line 4—4 of Fig. 1;

Fig. 5 is a sectional view on the line 5—5 of Fig. 1;

Fig. 6 is a diagrammatic view of the apparatus of the invention associated with a stock treating apparatus such as a Jordan; and

Fig. 7 is a wiring diagram.

Referring now to the drawings more in detail, the invention will be fully described.

A stock supply compartment is represented by 2 and a water compartment is represented by 4 and between these is a combining and delivery compartment 6 all of which will now be described.

The compartment 2 has a lower wall 8, end walls 10 and 11 and front and rear walls 12 and 14. A wall 16 between walls 10 and 11 extends

downwardly and terminates at a point above lower wall 8. Another wall 18 between said walls 18 and 11 extends upwardly from lower wall 8 and terminates at a distance upwardly from said lower wall. A gate 20 is slideable up and down relative to the wall 18 and a screw 22 having its lower end secured to said gate is in engagement with a nut 24 rotatable on a support 26.

The gate 20 as well as other gates to be described are such as used in and well known in paper mill machinery and have a screw in engagement with a nut which when rotated in one direction or the other raises or lowers the gate. An inlet 28 for stock is provided at the forward wall 12 and an outlet 30 extends from the rear wall 14.

Paper making stock is delivered through inlet 28 direct from the Jordan or other fiber treating machine during its operation and as said stock is delivered to a paper making machine or machines. Gate 20 is adjusted to provide the desired stock level and the overflow flows through the outlet 30.

Wall 11 is provided with an outlet 36, see Fig. 3, and a gate 38 is slideable relative thereto which has a screw 40 secured thereto. The screw has a nut 42 engageable therewith which rests on a bearing 44 secured to wall 11.

Water compartment 4 is similar to compartment 2 and has a lower wall 48, front and rear walls 50 and 52, and end walls 54 and 55. Downwardly and upwardly extending walls 56 and 58 extend between walls 54 and 55. A gate 60 is slideable relative to wall 58 and has a screw 62 extending through a bearing 64 and a nut 66 is in engagement therewith. A water inlet 68 extends through wall 50 and an outlet 70 extends from wall 52. Wall 55 is provided with an opening 72 and a gate 73 slideable relative thereto has a screw 74 slideable in a bearing 76 with a nut 78 in engagement therewith.

The combining compartment 6 has front and rear walls 80 and 82 between walls 11 and 52 and lower walls 84 merge into a delivery conduit 86. A perforated wall 88 extends between walls 80 and 82.

Stock delivered to compartment 2 from the stock refining apparatus flows through opening 36 in a predetermined volume and will be of a known consistency. The volume is controlled by adjustment of gate 38. Water flows through opening 72 in predetermined volume and is intermixed with the stock from outlet 36. The volume of water is controlled by gate 73. The perforated wall or baffle 88 brings about a thorough intermixing of stock and water.

With the consistency of the stock being known, the relative proportion of water mixed therewith may be varied as desired, it being desirable to use more water than stock. As an example, the proportion of stock and water may be one to ten so that errors in consistency of the stock is in the mixed stock reduced according to the proportion of stock and water.

Thus mixed stock and water with the consistency known and with any errors in original consistency reduced, is delivered through conduit 86 continuously while the stock treating machine is in operation and from which stock flows to compartment 2. The mixed stock and water to be called stock is delivered through conduit 86 to a mixing box 9 of the apparatus hereof. This apparatus will be relatively small and will preferably be located adjacent the stock refining or treating apparatus such as a Jordan.

Front and rear walls 82 and 84 and end walls 86 and 88 secured together provide a mixing box 9 and vat 11. A cylinder mold 100 having a foraminous surface 102 of any well known form has a shaft 105 rotatable in bearings 104 which may be driven by any suitable means such as a motor or other means which is common with paper machines.

Levers 106 pivoted at 107 to brackets 108 secured to the vat walls have a roll 110 journaled therebetween which is preferably yieldable. Weights 112 on the free ends of the levers 106 hold the levers and roll down and a doctor 114 between the levers removes the mat of fibers formed on the cylinder mold. A trough 116 receives the mat as it is removed and an outlet or discharge 118 extends from said trough. The material may be returned to the stock refining apparatus or delivered to the paper machine.

10 The ends of the mold are sealed to the side walls of the vat in the usual and well known manner as indicated by 120. A white water compartment 122 is formed at one side of the vat 11 by walls 124 and 126. Gates 128 and 130 are slideable relative to transverse walls 129 and 131 of the mixing box 9 and have screws 132 and 134 secured thereto which are slideable in bearings 136 fixed to supports 138. Nuts 140 in engagement with the screws are adapted on rotation to

15 move the screws and thereby the gates up or down.

20 The ends of the mold are sealed to the side walls of the vat in the usual and well known manner as indicated by 120. A white water compartment 122 is formed at one side of the vat 11 by walls 124 and 126. Gates 128 and 130 are slideable relative to transverse walls 129 and 131 of the mixing box 9 and have screws 132 and 134 secured thereto which are slideable in bearings 136 fixed to supports 138. Nuts 140 in engagement with the screws are adapted on rotation to

25 move the screws and thereby the gates up or down.

30 An overflow outlet 142 is provided at the lower side of the mixing box 9. The lower side of the mixing box and vat are connected to a conduit 35 144 which has a T 146 for clean out purposes. This facilitates washing and flushing out of the apparatus. A baffle 148 extends between walls 82 and 94 and a lower wall of the vat is concaved at 150 below the said baffle and then extends as at 40 152 downwardly and around the cylinder in the well known manner as shown in Fig. 2.

The apparatus is preferably small in size as compared to the size of a paper machine and is so connected to a stock refining machine as to receive stock therefrom as the stock is delivered to a paper making machine. The vat is generally similar to a cylinder paper making machine vat except that it may be modified for the practice of the invention and the cylinder mold 100 is driven in any well known manner as previously stated. It is intended that the mold be in rotation simultaneously with the operation of the refiner or machine to which the apparatus is connected. The various gates are constructed and operated as is customary with paper making machines.

45 As before stated, stock, that is water and paper making fibers, is delivered into compartment 2. Its consistency is known and the percentage of error is small. A predetermined ratio of water and stock are mixed in compartment 6 and is accomplished by adjustment of the gates associated with the compartments 2, 4 and 6. There will preferably be a sufficient ratio of water and stock to reduce any error in the consistency of the original stock.

50 The mixed stock flows from compartment 6 through pipe 86 to the mixing box 9 and the desired amount flows over gate 130 to the vat. The flow is controlled by adjustment of gate 130. Any excess flows over gate 132 and through pipe 142 to the refiner, stock chest of a paper making machine or wherever desired.

55 As the cylinder mold rotates a mat of fibers is taken on thereby which is couched by roll 110 and doctored by 114 into trough 116. White

water as usual flows into the white water compartment 122. The discharge from said compartment is shown at 123 in Fig. 2.

The level of stock in the vat and level of water in the white water compartment are related or have a differential dependent upon the freeness condition of the stock. According to the invention this differential indicates the freeness of stock and is employed to control or bring about adjustment of the stock refining apparatus, such as a Jordan, in order to bring about and maintain the desired freeness conditions of the stock.

As an example, where the stock is slow the level of white water in compartment 122 is a greater distance below the level of stock in the vat 11 than where the stock is more free. That is the differential between white water and stock levels is greater with slow stock than with stock which is relatively more free so that the differential is a result of the condition of the stock.

A certain or desired condition of freeness has a corresponding differential so that when that differential is attained and maintained the stock will be as desired. According to the invention, the refining apparatus is adjusted so as to bring about a differential in levels of stock and white water which is related to the freeness condition desired and as the stock flows continuously to the apparatus the varying conditions of freeness bring about variations in level differentials which are utilized to adjust the stock treating machine so as to result in a constant, uniform and predetermined freeness.

This may be accomplished by various means but for purposes of disclosure the following will suffice, see Figs. 6 and 7.

The vat 11 is shown in Fig. 6 as is a stock treating machine 160. The stock treating machine may take various forms but for illustration is a Jordan engine such as shown in U. S. Letters Patent No. 1,961,808 of June 5, 1934. Such a machine has a plug which is adjustable back and forth or longitudinally in a shell. The plug and shell carry coacting blades and the adjustment of the plug brings about various conditions of freeness of the stock being treated.

The adjustment of the plug is accomplished by means of a screw 162 in threaded engagement with a worm gear 164 operatively engaging a worm 166 fixed to a shaft 168 of a motor 170. As the motor rotates in one direction or the other the plug is moved thereby to adjust the plug relative to the shell.

According to this invention, the differential of level of stock in the vat 11 and of water in the white water compartment is utilized to control the operation of the refining apparatus. It may be accomplished in various ways but the following is for purposes of disclosure.

A float 174 is disposed in vat 11 and a float 176 is disposed in the white water compartment. These floats are carried by float rods 178 and 180 which have end extensions 179 and 181. The rods and their extensions are relatively swingable on a stationary pivot between the rods and extensions, as shown.

Outer ends of the extensions are pivotally connected to one end of links 184 as shown at 182 in connection with extension 181. Opposite ends of links 184 are pivotally connected to the upper end of a switch lever 186, as shown.

The switch lever at its lower end is pivoted on a stationary pivot, as shown, for swinging movements to engage either one of contacts 192 and 194.

As the level of stock increases or decreases, lever 178 is swung up or down and as the level of white water increases or decreases lever 180 is swung up or down. For a certain freeness of stock the levels of stock will have a certain relationship. A change in freeness results in a change in the relationship of the levels of stock and white water so that accordingly relative swinging of levers 178 and 180 results.

10 The motor 170 is of the reversible type adapted to rotate its shaft 168 in either direction thereby to move plug in or out relative to the shell. Connections 188 and 190 extend from the motor 170 to contacts 192 and 194 which are engageable by arm 186. A power supply represented by 198 is connected to the motor and switch arm as shown.

15 As the differential of levels in the vat and in the white water compartment becomes greater or less than normal or such as is related to the desired freeness of the stock, the switch arm is moved in one direction or the other to bring about rotation of the motor 170 and movement of the plug of the Jordan in one direction or the other. The action of the refiner then results in a different or 20 corrected freeness of stock so that the differential in levels becomes normal.

25 Variations in the differential of levels brings about relative movements of the floats which actuate the switch arm and thereby the motor is energized for moving the plug in one direction or the other. In this way the refiner is caused to produce stock of a desired condition of freeness so that the paper making machine is supplied with constant and uniform stock. Any desired 30 condition of freeness may be maintained so that the paper making machine is supplied with stock of the desired freeness and any changes in freeness are at once corrected.

35 The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

40 50 What it is desired to claim and secure by Letters Patent of the United States is:

1. The combination of stock treating apparatus for delivering stock to a paper machine and having adjustable means for varying the freeness of stock with apparatus for adjusting the means accordingly as the freeness of stock varies comprising, means to receive a portion of the stock, means to mix the stock with water in predetermined proportions and provide stock of certain consistency, a vat to receive the stock having a white water compartment and a foraminous mat forming element rotatable therein whereby a mat is formed on said element and different levels of stock and white water are provided in said vat and white water compartments, and means for operating the adjustable means actuated by the differential in the levels.

2. The combination of stock treating apparatus for delivering stock to a paper machine having adjustable means for varying the freeness of stock accordingly as the freeness of stock varies comprising, a compartment to receive a portion of the stock and a water compartment 55 60 65 70 75 80 85 90 95 99 separate therefrom, a mixing compartment for

stock and water, said compartments provided with adjustable means to control the relative proportions of stock and water delivered to said mixing compartment, a vat having a foraminous element rotatable therein and provided with a white water compartment, means for conducting mixed stock and water to said vat whereby a mat of paper making fibers is formed on said element and a differential in levels of stock and white water in said vat and white water compartment is provided according to the freeness of the stock, and means actuating the adjustable means operated by variations in level differential.

3. Apparatus for controlling the freeness of stock supplied a paper making machine from an adjustable stock treating machine comprising in combination, a stock compartment for receiving a portion of the stock from the stock treating machine, a separate water compartment, a mixing compartment for continually mixing stock and water and means for controlling the relation of stock and water in said mixing compartment to provide diluted stock of predetermined consistency, a vat having a rotatable foraminous cylinder continuously rotatable therein and provided with a white water compartment and connections therefrom to said vat, connections between said mixing compartment and vat whereby

diluted stock is continuously supplied said vat and a mat is formed on said cylinder and a differential of stock and white water levels exists according to the freeness of the stock, and means actuated by variations in the levels which is connected to and adapted to adjust the stock treating machine.
